UNITED STATES PATENT OFFICE.

WALTER WRIGHT, OF SAN FRANCISCO, CALIFORNIA, ASSIGNOR, BY MESNE ASSIGNMENTS, TO UNDERWOOD COMPUTING MACHINE COMPANY, OF NEW YORK, N. Y., A CORPORATION OF NEW YORK.

ADDING ATTACHMENT FOR TYPE-WRITING MACHINES

1,095,060.

Specification of Letters Patent.

Patented Apr. 28, 1914.

Application filed November 8, 1905. Serial No. 286,368.

To all whom it may concern:

Be it known that I, WALTER WRIGHT, a citizen of the United States, residing at San Francisco, in the county of San Francisco and State of California, have invented certain new and useful Improvements in Adding Attachments for Type-Writing Machines, of which the following is a specification.

10 This invention relates to an adding attachment for typewriting machines, and one of the objects of the invention is to provide a cheap, simple and compact device of this character which can be attached to any of 15 the standard forms of typewriting machines. In this class of machines, by depressing the numeral keys for the purpose of printing the numerals on the work-sheet, the numbers so printed on each line of writing are mechanically added to the numbers that have been 20 printed on the preceding lines of writing; and the total of all of the lines so written may be read off at any time.

It is often desired to write several 25 columns of figures side by side upon the same work-sheet, and to be able to read off the totals of these several columns whenever desired.

It is an object of my invention to produce 30 a machine by which it is feasible to write several columns at any selected places on the work-sheet, and also add them. I have provided a device whereby not only may a single ordinary wide column be written at 35 any place on the work-sheet and the total thereof secured, but also whereby several such columns may be written side by side where desired, and their results secured; and wide columns may alternate with narrow columns, and even be written very closely together on the work-sheet, and still the results secured by means of the adding mechanism. To do this, I provide an abacus-like set of computing wheels, which are 40 sufficiently numerous to permit apportionment of the set into a plurality of standard commercial totalizers (each of which comprises at least eleven computing wheels, including two wheels for decimals). These 45 wheels preferably occupy the entire writing space of the standard typewriter, that is, there may be one wheel for each letter-feeding movement of the typewriter. I connect 50 all of these wheels by means of carry-over

mechanism into an uninterrupted train, 55 whereby at the will of the operator numerous narrow columns, slightly separated one from another, may at one time be located at any selected points along the run of the carriage, and several wide columns may be 60 located along said run at another time, and many alternate wide and narrow columns may be located at still another time. In other words, the device is adapted for universal location of the columns, regardless of 65 the size of any column.

A further object is to provide an attachment very convenient for making out bills or statements in which it is necessary to specify the nature of each item, for with 70 the typewriter the character of the item can be written and the amount set opposite thereto, and so on for a number of items, and after all the items have thus been set down, then by means of the adding attachment, the total of such items is immediately 75 known and can be read off and written down.

A further object of the invention is to provide an attachment which will not interfere in any way with the ordinary operation 80 of the keys and with which it requires no more appreciable exertion on the part of the operator to press the numeral keys when intending to add the figures so written than when not, and in which the adding attachment can be brought into use simply by means of operating a control or shift key provided for that purpose. The attachment may therefore be used or not used at 85 any time as may be desired.

In the accompanying drawings, Figure 1 is a front elevation of a typewriting machine having my attachment secured thereto; Fig. 2 is a broken front view of a portion of the attachment; Fig. 3 is a similar 95 view of the same in a different position from that of Fig. 2; Fig. 4 is a broken view of the mechanism for winding the spring; Fig. 5 is a broken plan view upon an enlarged scale of the end of the typewriting 100 machine to which the attachment is applied; Fig. 6 is a broken plan view of the carriage showing the racks in a different position from that of Fig. 5; Fig. 7 is a detail perspective view of the shift mechanism for 105 bringing the attachment into operation; Fig. 8 is an end view of the attachment; Fig. 9 is a vertical section of a portion of

the attachment broken away; Fig. 10 is a broken detail view of a portion of the main shaft; Fig. 11 is a detail cross sectional view of the shaft; Fig. 12 is an enlarged broken 5 front view of the counting wheels on the shaft; Fig. 13 is a cross section thereof; Fig. 14 is a cross section of a modification.

Referring to the drawings, 1 represents the frame of a typewriting machine, which 10 may be of any standard construction, but, for the purpose of illustration is herein shown as an Underwood machine. Upon the right hand side of the frame is secured by screws 15 an extension or arm 3, which carries at its end a slideway 4 for a carriage 5. Said carriage moves in a direction longitudinally of the machine and supports two racks, a fixed rack 6 and a movable rack 7, which has a rib 8 sliding in a guideway in the carriage. 20 The carriage moves only the distance between the centers of said racks, and by its movements brings one or the other of said racks into engagement with a gear wheel 9 upon a shaft 10, said shaft rotating in a bearing 11 secured upon said arm and also 25 in a bearing 12 upon the end of an arm 13 extending outward from the other end of the typewriter frame, to which it is secured. When the gear wheel 9 is in engagement 30 with the fixed rack 6 it is thereby prevented from turning, but as soon as, by the movement of the carriage, it is brought into engagement with the movable rack 7, said gear wheel is no longer held back, and can 35 revolve. This it does under the action of a coiled spring 14 secured at its inner end to a fixed stud shaft 15 and at its outer end to a barrel 16 having a gear wheel 17 which meshes with a gear wheel 18 secured on the 40 other end of the shaft 10. This spring 14 is provided with the usual ratchet and can be wound up at intervals by a key or handle to provide sufficient power for the operation of the adding attachment. The motion 45 communicated to the shaft 10 by the spring 14 causes the gear wheel 9 to revolve, and thereby moves forward the movable rack, and the extent of this movement is variably limited from the same source as that which 50 initiates the movement of the carriage.

When it is desired to use the adding attachment, the operator depresses a shift key 20, which swings a bell crank lever 21 which is attached to the end of a bar 22, said bar 55 at the other end of being guided by a slot 23. Through said bar passes, for each numeral key, rod 24 depending from a bell crank lever 25. Each rod is bent at the lower end to form a hook 26 adapted to enter an eye 27 in 60 a loop 28 secured to the bar 29 of the numeral key. When said bar 22 is shifted to the left by the depression of the shift key, this movement brings all of said hooks 26 into 65 the eyes 27, so that upon the depression of any numeral key the corresponding rod

24 is also depressed. As soon as the shift key is released the bell crank lever 21 is returned to its original position by the action of a spring 30, and this returns said bar 22 to the right and withdraws said hooks out of said eyes, so that the adding device is no longer operative. But so long as the device is operative by pressure upon the shift key, the depression of any numeral key rocks the corresponding bell crank lever 25, so that the upwardly extending member thereof swings to the left. The top of said member is connected by a link 32 with the top of an idler arm 33 extending upward from a sleeve 34 on a stud 35 extending horizontally from the frame 36 secured upon the end of the typewriter frame, said sleeve having also another arm 37 connected by a link 38 loosely with a vertical lever 40. There are nine of these vertical levers 40, corresponding to the nine numeral keys on the typewriter, and arranged at regularly increasing distances from the slideway of the carriage. When any lever is thus moved to the left, it presses against an extension 41 secured to the carriage and thus also moves the carriage to the left, bringing the movable rack into engagement with the gear wheel, which permits the gear wheel to revolve and move the movable rack forward. The forward motion of said rack is limited by the next lever 40 to that which has shifted the carriage, which, as well as the other levers corresponding to higher numbers, have remained stationary, so that the extent of this motion depends upon the distance of said lever from the carriage slideway. For instance, for the numeral "1" for which the lever 40 is the nearest to the carriage slide, the rack is immediately stopped by the next lever corresponding to the numeral 2 after moving forward the distance of only one tooth. For the numeral 2 whose lever 40 is one step farther from the carriage slide the rack is stopped after moving through the distance of two teeth, and so on. The movement of any lever 40 causes all the levers 40 corresponding to lower numbers to be also moved, for the lever 40 has a small arm 42 projecting rearward along the back of the lever 40 corresponding to the next lower number, so that the movement to the left of any lever carries with it the lever corresponding to the next lower number, and so all the levers corresponding to the lower numbers are simultaneously moved with the movement of the lever corresponding to the selected number. It will thus be seen that the amount of revolution permitted to the gear wheel 9 and to the shaft 10 depends upon the numeral which is depressed. As soon as pressure is removed from the numeral key, so that it rises again, the carriage is returned to its original position by means of a spring 43 returning also the levers 40. This moves 70 75 80 85 90 95 100 105 110 115 120 125 130

- the movable rack 7 from underneath the gear wheel 9 and brings the fixed rack 6 underneath said gear wheel and thereby locks the gear wheel, preventing any further movement until another numeral key is depressed. Upon being released from engagement with the gear wheel, the movable rack is immediately returned to its original position by means of a spring 44.
- 10 The revoluble movement of the gear wheel 9 is utilized to add rows of figures in the following manner. Upon the typewriter carriage 45 are secured hangers or arms 46 which extend forward and downward through the lower ends of which the shaft 10 passes, which, between said ends, carries a number of counting or computing wheels 47, there being one such counting wheel for each space on the typewriting machine, of which, for a machine of ordinary width, there are about seventy. These counting wheels therefore move with the typewriter carriage.
- 15 The shaft carries at the center a toothed master wheel 48 having ten teeth corresponding to the ten digits, said teeth being adapted to enter corresponding recesses formed in the hub 49 of any one of the series of counting or computing wheels. These recesses form inwardly extending teeth 50, the ends of the teeth being substantially in contact with the shaft 10. By the revoluble movement imparted to the shaft from the depression of a key by the release of the movable rack in the manner already described, that counting wheel 47, which, by the movement of the typewriter carriage, has been brought to the center of the machine, and is therefore in operative engagement 20 with the toothed wheel 48 on the shaft, and moved through a corresponding angle. This appears by the advance of the numerals 51 formed upon the outer surface of the counting wheel.
- 25 The mechanism above described for determining the extent to which the counting or computing wheels will be rotated may be termed a "valuating mechanism" in that it coördinates the rotation of each computing wheel to correspond in extent to the numerical value of the numeral key actuated at any particular instant. It will be noted that this mechanism is located off to one side alongside the frame of the machine out 30 of the way of the typewriting mechanism and is joined to the latter by bare connections.
- 35 It is necessary to provide that after any counting wheel has been moved past the number 9, one tenth of a revolution should be imparted to the next counting wheel on the left. For this purpose each counting or computing wheel has a finger 52 which extends outward from the back or left hand surface of the counting wheel into an annular recess 53 formed in the next counting
- 40 wheel to the left, and is there adapted to engage a tooth 54 also extending into said recess laterally from the end of a thin metal arm 55, which has a slotted support on a rod 56 supported by the two hangers 46 which move the counters on the shaft 10. When any counting wheel has moved through a complete revolution so that it is necessary to advance the next counting wheel to the left through one-tenth of a revolution, said finger engages said tooth and causes the arm 55 to move with the first counting wheel through one-tenth of a revolution. At the beginning of such movement a pin 58, carried by said arm, extends to the left into the corner behind a tooth 59 of an internal ratchet wheel formed on the counter, so that, when said arm 55 has moved with the first counting wheel through one-tenth of a revolution, this pin 58, engaging the ratchet tooth, causes the counting wheel on the left to move also through one-tenth of a revolution. A further movement of the first counting wheel will cause the finger 52 to escape past the tooth 59 upon the thin metal arm, 45 releasing the same without advancing the second counting wheel any farther, and, as soon as released, a spring 60 returns said arm to its original position. To hold all the counting wheels stationary except those which are being positively advanced by the toothed wheel, there is provided for each counting wheel a brake 62 formed of a spring metal plate bearing against the side of the counting wheel. This plate is secured 50 to a sleeve 63 pinned to the shaft.
- 45 In the modification shown in Fig. 14, instead of the shaft being provided with a gear wheel it is formed with a decagonal enlarged portion 64 which fits in succession 55 into correspondingly shaped inner surfaces in the hub of the counting wheels.
- 50 In order to re-set the counting wheels to zero the shield 66 is raised and they are re-set by hand. However, any suitable mechanical re-setting mechanism may be used in conjunction with this invention.
- 55 It will be understood that the mechanism by which any counting wheel is advanced through one-tenth of a revolution by reason of the complete revolution of the preceding counting wheel, is not an essential part of the present invention, as any common mechanism for this purpose may be used.
- 60 I claim:—
1. In an apparatus of the character described, the combination with a typewriting machine, of a shaft, computing wheels movable thereon, said shaft having a part 65 adapted to engage any computing wheel and turn the same, means for turning said shaft, and means for limiting the extent of rotation of said shaft, comprising a gear wheel on the shaft and a carriage, said carriage 70

having a fixed rack and a movable rack arranged in alternate positions of the carriage to engage said gear wheel, and means for variably limiting the movement of the movable rack when brought into engagement with the gear wheel.

2. In combination with means for rotating a shaft, means for variably limiting the extent of rotation thereof comprising a gear wheel on the shaft, a carriage sliding in a direction parallel with the shaft, and having fixed and movable racks adapted in alternate positions of the carriage to engage said gear wheel, and means for variably limiting the extent of movement of the movable rack, when so engaging said gear wheel.

3. In combination with a shaft and means for rotating the same, a gear wheel rotating with the shaft, a carriage moving parallel with the axis of the gear wheel and having a fixed rack and a movable rack, and means for limiting the extent of movement of the movable rack.

4. In combination with a computing wheel, a shaft for advancing the same, means for rotating said shaft, and means for permitting said shaft to rotate while limiting the extent of rotation thereof, comprising a gear wheel rotating with the shaft, a carriage moving parallel with the axis of the gear wheel, fixed and movable racks on said carriage, a series of levers for shifting said carriage to move the fixed rack out of engagement with the gear wheel and the movable rack into engagement therewith, and means for variably arresting the movement of the movable rack corresponding with the lever so operated.

5. In combination with a computing wheel, a shaft for advancing the same, means for rotating said shaft, and means for permitting said shaft to rotate while limiting the extent of rotation thereof, comprising a gear wheel rotating with the shaft, a carriage moving parallel with the axis of the gear wheel, fixed and movable racks on said carriage, a series of levers for shifting said carriage to move the fixed rack out of engagement with the gear wheel and the movable rack into engagement therewith, means controlled at the will of the operator for connecting said levers with typewriter keys, and means for variably arresting the movement of the movable rack corresponding with the lever so operated.

6. In combination with a computing wheel, a shaft for advancing the same, means for rotating said shaft, and means for permitting said shaft to rotate while limiting the extent of rotation thereof, comprising a gear wheel rotating with the shaft, a carriage moving parallel with the axis of the gear wheel, fixed and movable racks on said carriage, and a series of levers for shifting said carriage to move the fixed

rack out of engagement with the gear wheel and the movable rack into engagement therewith, each lever shifting with it the lever corresponding to a lower number, the next higher unshifted lever acting as a stop 70 for the movable rack.

7. In a computing machine, the combination with keys, of a computing mechanism controlled thereby, including an escapement wheel and fixed and movable racks, a power-driven actuator or master wheel to turn the number wheels, and key-operated members in a group comprising one to be moved directly and also arranged to be moved by another, and having means to move the 80 fixed and movable racks relatively to the escapement wheel and also determining the extent of movement of the movable rack by means of the unmoved members.

8. In a combined writing and adding machine, the combination with a letter-feeding carriage, of a computing mechanism comprising an abacus-like set of computing wheels which are sufficiently numerous to permit apportionment of the set into a plurality of standard commercial totalizers, each whereof comprises at least eleven computing wheels and a carry-over mechanism connecting all of said computing wheels into an uninterrupted train, whereby, at the 90 will of the operator, numerous narrow columns, slightly separated one from another, may at one time be located at any selected points along the run of the carriage, and several wide columns may be located along 100 said run at another time.

9. In a combined writing and adding machine, the combination with a letter-feeding carriage, of a computing mechanism comprising an abacus-like set of computing 100 wheels which are sufficiently numerous to permit apportionment of the set into a plurality of standard commercial totalizers, each whereof comprises at least eleven computing wheels and a carry-over mechanism 110 connecting all of said computing wheels into an uninterrupted train, whereby, at the will of the operator, numerous narrow columns slightly separated one from another, may at one time be located at any selected points 115 along the run of the carriage and several wide columns may be located along said run at another time said set comprising also a much greater number of connected computing wheels than necessary to a plurality of commercial totalizers, to permit location of the adding columns at different positions along the run of said carriage.

10. A computing mechanism comprising an abacus-like set of computing wheels, 125 which are sufficiently numerous to permit apportionment of the set into a plurality of standard commercial totalizers, each whereof comprises at least eleven computing wheels, whereby, at the will of the operator, 130

numerous narrow columns, slightly separated one from another, may at one time be located at any selected points, and several wide columns may be located at another time, and tens-carrying devices extending throughout the entire set to enable tens to be carried between any adjoining wheels in the set.

11. The combination with a gang of computing wheels, of a master wheel for driving said computing wheels, and an escapement mechanism for said master wheel including a gear, fixed and movable racks meshing with said gear to determine the silencing or activity of said master wheel, and shifting means for effecting a relative movement between said racks and said gear to alternatively bring about a meshing of said gear with either said fixed rack or said movable rack.

12. The combination with a gang of computing wheels, of a master wheel for driving said computing wheels, and an escapement mechanism for said master wheel, including a gear, a fixed rack, a movable rack, shifting means for effecting a relative movement between said gear and said racks to alternatively bring about a meshing of said gear with either said fixed rack or said movable rack, and means for determining the extent of movement of said movable rack when meshing with said gear.

13. The combination with a gang of computing wheels, of a master wheel for driving said computing wheels, and an escapement mechanism for controlling the movement and extent of movement of said master wheel, comprising a gear, fixed and movable members alternatively meshing with said gear, and shifting means for moving one of said members into engagement with said gear and concomitantly moving the other of said members out of engagement with said gear, so as to determine the rotation and non-rotation of said gear and said master wheel.

14. The combination with a gang of computing wheels, of a master wheel for driving said computing wheels, and indexing or valuating means for determining the extent of rotation of said master wheel, said valuating means including a gear, a rack meshing with said gear, and a series of fingers located in the path of movement of said rack to obstruct the movement of said rack at different points corresponding to different digits.

15. The combination with a gang of computing wheels, of a master wheel for driving said computing wheels, indexing or valuating means for determining the extent of rotation of said master wheel, said valuating means including a gear, a rack meshing with said gear, and a series of fingers located in the path of movement of said rack

to obstruct the movement of said rack at different points corresponding to different digits, and a series of keys, one individual to each of said fingers for moving its corresponding finger and all preceding fingers out of the path of said rack.

16. The combination with a gang of computing wheels, of a master wheel for rotating said computing wheels, a motor for driving said master wheel, and a valuating or indexing mechanism for determining the extent of rotation of said master wheel by said motor, said valuating mechanism including a gear, a drivable member meshable with said gear and a series of interfering members located in the path of movement of said drivable member to obstruct the movement of said drivable member at various points.

17. The combination with a gang of computing wheels, of a master wheel for rotating said computing wheels, a motor for driving said master wheel, a valuating mechanism for determining the extent of rotation of said master wheel by said motor, said valuating mechanism including a gear, a drivable member meshable with said gear, and a series of interfering members located in the path of movement of said drivable member to obstruct the movement of said drivable member at various points, and a series of numeral keys one individual to each of said interfering members to shift them between interfering and non-interfering positions.

18. The combination with a gang of computing wheels, of a master wheel for rotating said computing wheels, a motor for driving said master wheel, a valuating mechanism for determining the extent of rotation of said master wheel by said motor, said valuating mechanism including a gear, a drivable member meshable with said gear and a series of interfering members located in the path of movement of said drivable member to obstruct the movement of said drivable member at various points, and a series of numeral keys, one individual to each of said interfering members to shift them between interfering and non-interfering positions, said interfering members having means to remove all preceding interfering members out of the path of said drivable member.

19. The combination with a typewriting machine having a letter-feeding carriage, of a series of computing wheels extending across the front of said machine and connected to said carriage to travel therewith, a non-traveling master wheel, a master wheel shaft extending from right to left of the typewriting machine and beyond the sides thereof, motive means for said master wheel shaft connected thereto at one extremity thereof and at one side of the typewriting machine, and an escapement mechanism for

said master wheel shaft connected thereto at the other extremity of said shaft and located at the other side of said typewriting machine, said computing wheels mounted to travel between said motive means and said escapement mechanism.

20. In a typewriting and computing mechanism comprising a letter-feeding typewriter carriage and also comprising a keyboard at the front of the machine and having numeral keys, and also comprising a series of computing wheels, said series arranged across the machine at the front thereof and above the keyboard, and a master-wheel to engage and drive said computing wheels, the combination with an indexing mechanism for said master-wheel, said indexing mechanism mounted at one side of the typewriter at the front thereof and connected to said 20 master-wheel, of bell cranks connected to said keys, and links extending from said bell

cranks across the machine to connect with said indexing mechanism.

21. In a computing machine, a master wheel shaft prolonged at each end beyond 25 its master wheel and the corresponding set of computing wheels, means at one end of the shaft to operate it by power, an escapement mechanism at the other end of the shaft, key-links extending to the end of the 30 shaft that extends to the escapement mechanism, a part 40 to form part of the escapement mechanism, and means to enable the key-links to drive the part 40 variably.

In witness whereof I have hereunto set 35 my hand in the presence of two subscribing witnesses.

WALTER WRIGHT.
